(Cl. D48—31)

FIGURE 1 is a perspective view of a street signal base showing my new design, the side opposite not shown being substantially the same, and with the central portion broken away in part to indicate indeterminate length.

The side of the street signal bases not shown is substantially the same in appearance as the side shown.

I claim:

The ornamental design for a street signal base, as shown and described.
